W. C. SMITH.

AUTOGRAPHIC REGISTER.

APPLICATION FILED DEC. 15, 1919.

1,381,140.

Patented June 14, 1921.

Fig. 1.

UNITED STATES PATENT OFFICE.

WILLIAM C. SMITH, OF CHICAGO, ILLINOIS.

AUTOGRAPHIC REGISTER.

1,381,140.

Specification of Letters Patent. Patented June 14, 1921.

Application filed December 15, 1919. Serial No. 344,897.

To all whom it may concern:

Be it known that I, WILLIAM C. SMITH, a citizen of the United States, residing at Chicago, in the county of Cook and State of Illinois, have invented new and useful Improvements in Autographic Registers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in autographic registers of the type in which sliding means is employed for feeding out forms in a horizontal plane, an object being to provide a register of this character which 20 may be readily operated when inserted in a desk so as to be flush therewith.

A further object is to provide a register capable of feeding out the various lengths of forms ordinarily employed in these 25 machines.

A further object is to provide a register with feeding teeth of such proportions, and an anti-friction roll mounting of such construction, as to preclude the possibility of 30 hole tearing in feeding out perforated forms.

A further object is to provide a register with teeth mounted to move substantially horizontally and vertically for feeding out 35 and alining perforated forms, respectively.

A further object is to provide a register with form feeding and alining teeth projecting from a reciprocating severing blade in such a manner as to readily release forms 40 when fed out thereby.

A further object is to provide a register with a reciprocating severing blade having feeding teeth depending therefrom in normal engagement with the holes of perforated 45 forms for resisting the pull incident to severance.

A further object is to provide a register with a reciprocating severing blade having teeth for engaging and feeding out perforated forms in a straight line, and with means for so manipulating said blade that the teeth thereof will enter the holes of succeeding forms and effect registration thereof.

55 And a further object is to provide a register with means for raising and lowering a

reciprocating severing blade at the end of the return stroke thereof after perforated forms have been fed out in a straight line by means of teeth depending from said blade, 60 whereby said teeth will enter the holes of succeeding forms. Other objects will appear hereinafter.

With these objects in view my invention consists in the novel construction, combination and arrangement of parts, all as will be described hereinafter and more particularly pointed out in the appended claims.

An embodiment of my invention is shown in the accompanying drawing forming a part of this specification, and in which Figure 1 is a perspective view of the register showing by dotted lines a feeder and forms fed out thereby. Fig. 2 is a perspective view of said feeder. Fig. 3 is a vertical longitudinal section taken through the register showing roll mounting means. Fig. 4 is a transverse section taken through the register on line 4—4 of Fig. 3. Fig. 5 is a fragmentary top plan view showing means for manipulating said feeder. Fig. 6 is a fragmentary rear elevation showing locking means for the register cover. And Fig. 7 is a detail transverse section showing the construction of a spring catch for said feeder.

The preferred form of construction as shown in the drawing comprises side frames 1 having bearings 2 formed integral therewith for the reception of journals 3. These journals are adapted to roll along guide flanges 4, during the insertion of the paper rolls from the rear of the machine, and are formed integral with plugs 5 inserted in pasteboard roll cores 6. The curvature of bearings 2 is such as to permit rolls 7 to move bodily a short distance to the rear in case of a sudden pull on the perforated forms 8 during the initial feeding thereof. The inertia of rolls 7 is thus overcome without hole tearing, it being clear that rolling friction of journals 3 is less than sliding friction thereof. In effecting this result journals 3 roll up a slight incline in bearings 2. From rolls 7 forms 8 are passed over idler rolls 9 on to a writing table 10, which is secured to side frames 1 and provided with teeth clearance notches 11 at the front end thereof. The usual carbon paper housing 12 is secured to one side of the machine, as shown in Figs. 3 and 4.

An L-shaped cover 13, provided with the usual opening to expose the forms on table

22
10, is hinged at 14 to side frames 1 and locked in operative position by means of a thumb-screw 15, the head of which registers with a slot 16 when turned at right angles 5 for raising said cover. One edge of cover 13 is provided with a depending flange 17 for coöperation with a rolled up edge 18 of a feeder slide 19 in forming a slidable hinged connection. A severing blade 20 forming a 10 part of the feeder is disposed at right angles to slide 19 and formed integral therewith. Feeding teeth 21 depending from blade 20 are tapered and inclined forwardly in order to facilitate form adjusting and to maintain 15 engagement of the forms during the feeding operation.

The form feeder is reciprocated by means of a knob 22 projecting upwardly from the rear end of slide 19, as shown in the several 20 views. The forward movement of the feeder is arrested by a projection 23 at the rear extremity of slide 19 coming into contact with a screw 24, said movement being equal to the length of a form. The return stroke 25 or rearward movement is arrested by a shoulder 25 contacting with the front edge of cover 13, as shown in Figs. 2 and 3.

Prior to the completion of the return stroke of the feeder, the rear edge of projection 23 will slide up the inclined surface of a gravity cam 26 for raising severing blade 20 and teeth 21, as indicated by dotted lines in Fig. 6. This action will prevent teeth 21 from touching and disturbing the 35 arrangement of the fed out forms which hang at the front of the machine after disengaging the feeder. The bar at the front end of cover 13 and the frictional resistance of the carbon sheets (not shown) interleaved 40 with the forms are found to be amply sufficient means for holding said forms in place during the return stroke of the feeder. Cam 26 is adapted to move freely by means of an integral stem 27 journaled in a block 28, as 45 shown in Fig. 5. This block is mounted on cover 13 and forms a housing for a spring catch 29, which serves to lock the feeder after projection 23 has passed cam 26 and been depressed into the position shown; said 50 catch having a headed stem 30. It will be seen that depression of projection 23 lowers severing blade 20 and teeth 21 for engaging and adjusting the succeeding forms.

In order to adjust the machine to accommodate different lengths of forms, a plurality of screw-holes 31 are provided for the reception of screw 24. And, in order to insert rolls 7, it is apparent that cover 13 must be turned back to a vertical position.

60 The operation for feeding forms is as follows: Assuming that rolls 7 are in position and that forms 8 terminate at severing blade 20, then, upon pushing knob 22 forward until the movement is arrested by screw 24, a 65 set of forms will be fed out of the machine.

Instantaneous disengagement of the forms from teeth 21 is facilitated by gravity, the inherent tendency of the forms to curl upward, the inclination of said teeth, and also the rebound of the feeder after striking screw 24. The back stroke of the feeder instantly follows the outstroke and completes the operation, excepting severance of the forms. The operation as set forth is perfectly natural and simple in the extreme, 75 there being nothing to release prior to the feeding operation.

It will be observed that when projection 23 is moved forward, cam 26 automatically raises and offers no resistance to the passage 80 of said projection.

While the heads of forms 8 are shown at the front of the machine, said forms may be printed so that the heads will be at the other end thereof, in which case the operator 85 would pull knob 22 for feeding forms. In other words, the register may be a push or pull feed machine as desired or determined by circumstances.

And, while I have illustrated and described the preferred form of construction for carrying my invention into effect, there might be variations and modifications without departing from the spirit of the invention.

I, therefore, do not wish to be limited to the details of construction set forth, but desire to avail myself of such variations and modifications as come within the scope of the appended claims.

Having described my invention, what I claim as new is:

1. An autographic register employing perforated form strips comprising a reciprocating severing blade and operating means therefor, and means carried by said blade for engaging form holes and feeding out forms.

2. An autographic register employing perforated form strips comprising a reciprocating severing blade and operating means therefor, and teeth depending from said blade for engaging form holes and feeding out forms.

3. An autographic register employing perforated form strips comprising a reciprocating severing blade and teeth movable therewith for engaging form holes and feeding out forms, and operative means for moving said blade the length of a form.

4. An autographic register employing perforated form strips comprising a severing blade extending normally across said strips, teeth on said blade in normal engagement with form holes, and operative means for moving said blade and teeth the length of a form for feeding said strips.

5. An autographic register employing perforated form strips comprising a severing blade extending normally across said strips,

teeth depending from said blade in normal engagement with form holes, and operative means for moving said blade and engaged forms the length of a form.

5 6. An autographic register employing perforated form strips comprising a severing blade disposed normally over said strips, teeth depending from said blade in normal engagement with form holes, and operative means for moving said blade in a straight line for feeding out forms engaged with said teeth.

10 7. An autographic register employing perforated form strips comprising a severing blade extending transversely over said strips, teeth depending from said blade in engagement with form holes, and a slidable means carrying said blade for moving the same the length of a form.

20 8. In an autographic register employing perforated form strips, a form feeder comprising a severing blade extending transversely over said strips and a longitudinal slide therefor, teeth depending from said blade in normal engagement with form holes, means for moving said feeder the length of a form for feeding the engaged forms, a stop for limiting the movement of said feeder and facilitating disengagement 25 of said teeth, and means for engaging said teeth with succeeding forms.

30 9. In an autographic register employing perforated form strips, a form feeder comprising a reciprocating severing blade and a longitudinal slide therefor, means for operating said slide, teeth depending from said blade in normal engagement with form holes, a slide stop for facilitating disengagement of said teeth, and means coöperating 35 with said slide for facilitating engagement of said teeth with succeeding forms.

40 10. In an autographic register employing perforated form strips, a form feeder comprising a severing blade extending normally across said strips and a mounted slide therefor, means for moving said slide the length 45 of a form, tapered teeth depending from said blade in normal engagement with form holes, a stop for arresting the feeding movement of said slide and facilitating disengagement of said teeth, and means coöperating 50 with said slide for engaging said teeth with succeeding forms.

55 11. In an autographic register employing perforated form strips, a form feeder comprising a longitudinally movable severing blade and a slide therefor, inclined tapered teeth depending from said blade in normal engagement with form holes, means for 60 limiting the movement of said feeder to the length of a form and for disengaging said teeth, and means coöperating with said slide for effecting teeth engagement with succeeding forms.

65 12. In an autographic register employing

perforated form strips, a form feeder comprising a reciprocating severing blade and teeth depending therefrom in normal engagement with form holes, a mounted slide extending rearwardly from one end of said blade, means for moving said feeder forwardly for feeding out engaged forms and rearwardly for registration with succeeding forms, means for disengaging said teeth, and means for engagement thereof with succeeding forms.

70 13. In an autographic register employing perforated form strips, a form feeder comprising a transverse severing blade and a mounted slide disposed at right angles thereto, teeth depending from said blade in normal engagement with form holes, means for moving said feeder slide the length of a form, a stop for arresting the feeding movement and disengaging said teeth, and 80 means for lifting said blade for facilitating teeth engagement with succeeding forms.

85 14. In an autographic register employing perforated form strips, a form feeder comprising a transverse severing blade and tapering forwardly inclined teeth depending therefrom in normal engagement with form holes, a hinged slide carrying said blade and means for moving the same the length of a form forwardly and rearwardly, 90 a stop for limiting the forward movement of said slide and facilitating disengagement of said teeth, and means for tilting said slide during rearward movement thereof for carrying said teeth over succeeding forms 95 into registration with the holes thereof.

100 15. In an autographic register employing perforated form strips, a form feeder comprising a severing blade and a hinged slide disposed at right angles to one end thereof for moving the blade the length of a form, form adjusting feeding teeth depending from said blade in normal engagement with form holes, an adjustable stop for arresting the movement of said slide and facilitating 105 teeth disengagement, and a gravity cam for tilting said slide to facilitate teeth engagement with succeeding forms.

110 16. In an autographic register employing perforated form strips, a form feeder comprising a severing blade and teeth thereon in normal engagement with form holes, a hinged slide disposed at right angles to one end of said blade and extending rearwardly therefrom, means for moving said slide forwardly and rearwardly, a stop and a projection on said slide adapted to contact therewith for arresting forward movement and facilitating teeth disengagement, and a gravity cam arranged in the path of said 115 projection for tilting said slide and blade to carry said teeth over succeeding forms 120 and into engagement therewith.

125 17. In an autographic register employing perforated form strips, teeth in normal en- 130

gagement with form holes and means for moving the same for feeding the engaged forms, bearings for form rolls from which said strips are unwound, and means in said 5 bearings for permitting bodily movement of said rolls when said teeth are suddenly moved, whereby hole tearing is prevented.

18. In an autographic register employing perforated form strips, teeth in normal engagement with form holes and means for moving the same forwardly for feeding engaged forms, bearings for form rolls from which said strips are unwound, upwardly and rearwardly extending surfaces leading 10 from said bearings, roll journals normally resting in said bearings adapted to roll up said surfaces when undue tension is brought to bear on said strips, and journal guideways leading to said bearings from the rear 15 of the register to facilitate insertion and removal of the rolls.

19. In an autographic register employing perforated form strips, an L-shaped feeder comprising a transverse severing blade and 25 a longitudinal slide, teeth depending from said blade in normal engagement with form holes, means for moving said slide, and an adjustable stop therefor, whereby different lengths of forms may be fed out.

30 20. In an autographic register employing perforated form strips, an L-shaped feeder comprising a transverse severing blade and a longitudinal slide, a pair of teeth depending from said blade in normal engagement 35 with form holes, a handle on said slide for pushing the feeder the length of a form, means for disengaging said teeth, and means coöperating with said slide for guiding said blade and teeth over succeeding forms prior 40 to engagement therewith.

21. In an autographic register employing perforated form strips, an L-shaped feeder comprising a severing blade extending over the front end of the register table and a rearwardly extending slide movable on a longitudinal axis, means for locking said slide so 45 that the cutting edge of said blade is held in close proximity to said table for facilitating the severing operation, a pair of teeth depending from said blade in normal engagement with form holes, there being notches in said table to provide clearance for said teeth, means for reciprocating said feeder, means 50 for disengaging said teeth, and means for 55 engaging said teeth with succeeding forms.

22. In an autographic register employing perforated form strips, an L-shaped feeder comprising a transverse severing blade and a slide member hinged on a longitudinal axis, teeth depending from said blade normally engaging form holes, said slide being disposed at one side of the register writing space, a handle at the rear end of said slide for reciprocation thereof, means for teeth disengagement, and means for engaging said 60 teeth with succeeding forms.

23. In an autographic register employing perforated form strips, an L-shaped feeder comprising a transverse severing blade and a slide extending rearwardly from one end thereof, said slide being mounted to move longitudinally and to tilt on a longitudinal axis, a pair of forwardly inclined teeth depending from said blade in normal engagement with form holes, a handle at the rear end of said slide for reciprocating the feeder, adjustable means for limiting the movement of said feeder and effecting disengagement of said teeth, and means for tilting said slide prior to teeth engagement with succeeding 70 forms.

24. In an autographic register employing perforated form strips, a longitudinally movable L-shaped feeder and means for limiting the movement thereof to the length of 85 a form, means provided on one arm of the feeder for engaging form holes and feeding forms, a hinge and slideable connection for the other arm, and means for tilting the feeder to facilitate form engagement.

90 25. In an autographic register employing perforated form strips, an L-shaped feeder mounted for longitudinal and tilting movement and operating means therefor, teeth depending from one arm of the feeder in 95 normal engagement with form holes, an inward projection provided on the free end of the other arm and an adjustable stop arranged in the path thereof, a gravity cam arranged to coöperate with said projection 100 for tilting the feeder, and means for locking the feeder after the tilting movement thereof.

In witness whereof, I have set my hand this 12th day of December, 1919.

WILLIAM C. SMITH.
